UNITED STATES PATENT OFFICE.

JAMES W. LAYTON, OF SPRINGFIELD, ILLINOIS.

OIL KIT.

1,353,920.

Specification of Letters Patent. Patented Sept. 28, 1920.

Application filed June 7, 1920. Serial No. 387,049.

To all whom it may concern:

Be it known that I, JAMES W. LAYTON, a citizen of the United States, residing at Springfield, in the county of Sangamon and State of Illinois, have invented a new and useful Oil Kit, of which the following is a specification.

The invention relates to improvements in oil kits such as are used by locomotive engineers and others.

The purposes of the invention are: to provide a portable kit comprising a carrying case or container, an engineer's torch, an engineer's oil can, and a bucket containing a supply of oil, all compactly arranged and locked to prevent unauthorized use of the articles; to provide a lockable case of improved construction adapted to contain and prevent displacement of the several articles; to provide in conjunction with an oil bucket having a bail, means whereby the bail of the oil bucket may be utilized to carry the kit; and to provide means for holding the torch in such position that it may be lighted without taking it from the case.

The invention is illustrated in the annexed drawing to which reference is hereby made and will now be described and the novel features thereof will be recited in the claims.

Figure 1 is a perspective view of a kit embodying my invention; Fig. 2 is a vertical longitudinal section on the line 2. 2. of Fig. 1; and Fig. 3 is a vertical transverse section on the line 3. 3. of Fig. 1. The same reference numerals designate the same parts in all the views.

The case, which will be preferably made of galvanized sheet metal, comprises a bottom plate 4, having upturned side members 5 and upturned end members 6; angular corner posts 7, 8, 9 and 10 permanently attached to the members 5 and 6; a side plate 12 permanently attached to the upper ends of the corner posts 7 and 8 and extending upwardly somewhat above the upper ends of the posts; a side rail 13 permanently attached at the upper ends of the posts 9 and 10; a cross plate 14 permanently attached at the upper ends of the posts 8 and 10; a cross piece 15 permanently attached at the upper ends of the posts 7 and 9; and a cover 16 having a downwardly turned longitudinal member 17 and a downwardly turned end member 18. The member 18 has a hole 20 in line with a hole 19 in

the cross plate 14. A padlock 21 has a shackle 22 which occupies the holes 19 and 20 and connects the cover with the case. An upright 41 permanently attached to the plate 12 and one member 5 of the plate 4, and an upright 42 permanently attached to the side rail 13 and the opposite member 5 of the plate 4, stiffen the frame.

A bucket 24, to contain a supply of oil, rests on the bottom 4. The bucket has a conical part 25 which extends upwardly through an opening 23 in the cover 16. The diameter of the opening 23 is less than the diameter of the body of the bucket and will not admit of lifting the bucket outwardly through the opening. A bail 27 hooks into ears 26 stationary on the part 25 and is usable to carry the kit. The cover 16 has an opening 28 adapted to accommodate the outwardly extended neck 30 and the outwardly extended filler-tube 31 of the oil can 29. The diameter of the opening 28 is less than the diameter of the body of the oil can and does not admit of withdrawing the can through the opening.

Each of the rear corner posts 7 and 9 has an upwardly extended member 32 having a hole 33. Fingers 34 secured on the cover 16 extend through the respective holes and prevent lifting of the cover.

On the under side of the cover 16 is a stationary hood 35 in the form of a truncated cone, which surrounds the screw-cap 38 of the torch 37 and prevents displacement of the torch within the case. The torch is such as is commonly used by locomotive engineers. Here it is to be noted that the torch is so situated in the case that its wick tube 39 projects outwardly beyond the end of the case in such position that the wick 40 may be easily lighted without removing the torch from the case. The described position of the torch relative to the case and the lock is of practical value, because it will often be necessary to use the kit at night, and in that case the flame of the torch will illuminate the lock 21 so that it may be conveniently unlocked and detached from the case, thus affording access to the utensils contained in the case.

The mode of using the kit is as follows: The cover 16 having been first detached, the bucket 24, the can 29 and the torch 37 will be placed on the floor 4 in proper relation to each other, substantially as shown; the cover

16 will be placed in such position that the part 25 will project upwardly through the opening 23 and the parts 30 and 31 will project upwardly through the opening 28; the 5 cover will then be slid to the right to cause the fingers 34 to engage in the holes 33 of the members 32 and to cause the hole 20 to register with the hole 19; the shackle 22 of the lock 21 will then be inserted through 10 the holes 20 and 19 and its free end will be inserted in the lock and the lock will then be locked to securely connect the parts. To remove the utensils from the case, the procedure just described will be reversed.

15 It is obvious that minor details of construction may be varied without departure from my invention. I therefore do not restrict the claims to the precise details of construction herein set forth, but wish to 20 avail myself of such minor variations as are within the scope of my invention.

Having fully described my invention, what I claim as new and desire to secure by Letters Patent is:

25 1. A kit comprising a case; an oil bucket having a conical top, ears on said conical top and a bail engaged in said ears; an oil can

having a neck and an elongated nozzle and a filler tube; a torch having a cap; a cover 30 detachably connected with the case and having openings accommodating the conical part of the bucket and the neck and the filling tube of the oil can; and an inwardly extended hood attached to the cover and accommodating the cap of the torch. 35

2. A kit comprising a case; an oil bucket having a conical top; an oil can having a neck and a filling tube, and a torch having a cap, in the case; a cover detachably connected with the case and having openings 40 accommodating the conical top of the oil bucket and the neck and the filling tube of the oil can; an inwardly extended hood attached to the cover and accommodating the cap of the torch; and means for securing the 45 cover on the case.

In witness whereof I have hereunto signed my name at Springfield, Illinois, this 14th day of January, 1920.

JAMES W. LAYTON.
